UNITED STATES PATENT OFFICE.

MARIUS GUYOT, OF CLEVELAND, OHIO, ASSIGNOR TO ALUMINUM COMPANY OF AMERICA, OF PITTSBURGH, PENNSYLVANIA, A CORPORATION OF PENNSYLVANIA.

MOLD FOR CASTING METALS.

Application filed April 13, 1925, Serial No. 22,590. Renewed February 29, 1928.

This invention relates to multipart permanent molds for casting metals having melting points as high as or higher than aluminum and its alloys.

5 It also relates to a multiple part mold for casting metals which is provided with means to maintain the original alignment of unequally heated, cavity forming, hinged mold parts under different conditions of 10 temperature.

It also relates to a mold for making a plurality of metal castings which is provided with a plurality of removable core pins and means for reciprocating a plurality of said 15 pins.

It further relates to a compound gate having a common inlet passage for a multiple mold for casting high melting point metals having a high crystallization shrink- 20 age.

It further relates to a new and improved mold base for a permanent mold having two mold halves and a plurality of casting cavities therebetween.

25 In the drawings attached to and forming a part of this specification in which one form of apparatus embodying the present invention is shown—

Figure 1 is a top plan view of a multiple 30 piston mold.

Figure 2 is a side view partly in elevation and partly in section taken on line 2—2 of Fig. 1.

Figure 3 is a sectional view taken on line 35 3—3 of Fig. 1.

Figure 4 shows in detail the core pin actuating mechanism, and

Figures 5 and 6 are respectively longitudinal and transverse sectional views of a 40 slightly modified mold base.

The mold herein illustrated consists of a mold base indicated as an entirety by the character 1, made up of a bottom member 2 and a top member 3. Although members 2 and 3 may be variously connected, even in some cases being integral, I prefer to form them separately, as shown in the drawings, and secure them together by securing means, such as cap screws 4. As shown in Fig. 2, 45 the base members 2 and 3 are spaced apart and the top member 3 is provided with two holes 5 through each of which projects a pilot 6 which is capable of limited movement therein. The lower end of the pilot 6 rests on the top surface of bottom member

2 and has an outstanding shoulder 6^a or flange to prevent removal of the pilot from opening 5. It will be observed that the opening 5 is somewhat larger in diameter than the diameter of the part of the pilot 60 which passes therethrough so that pilot 6 is free to move in the mold base 1 to a limited amount. The top surface of the pilot 6 is preferably larger than the casting cavity of which it forms one end wall. Through the 65 center of the pilot 6 a hole 7 is provided which, when fitted with a plug 8 having a serrated outer surface, is adapted to permit the escape of air from the bottom of the casting cavity as the molten metal enters. This opening 7 may also be utilized to 70 form a machining boss on the end of the casting.

At one end of the mold base 1 is provided an upstanding hinge pin 9 which is removably fixed to the mold base by a nut 10 which clamps the mold base 1 between the shoulder 11 on the pin 9 and the nut 10. Two cooperating mold halves 12 and 13, which are alike in substantially all particulars, are 80 hinged at one end to the pin 9 and rest on and are movable on the top surface of member 3. These members are provided at their ends, opposite the pin 9, with means for locking them together, which means comprises a locking bar 14 loosely mounted at one end on mold half 13 as by a cap screw 15 and loosely carrying at its other end an arm 16 secured thereto as by a cap screw 17. The end surface 18 of the arm 16 is preferably a cam surface so that when it engages with the adjacent outer surface of the mold half 12 or with a wear plate 19 secured to such surface, locking pressure may be exerted on the mold half 12 to bring the two mold halves together. Arm 16 when released from locking engagement with mold half 12 may be lifted, carrying with it the locking bar 14, and then used to move the mold half 13 away from the mold half 12. A handle 20 secured to mold half 13 may be used for a similar purpose while handle 21 fastened to mold half 12 may be used to move this mold half across the top surface of the mold base 1. 105

The lower surfaces of the mold halves are cut away as at 12^a and 13^a to receive the parts of pilots 6 which project above the top surface of member 3. The mold halves, however, closely engage the pilots when 110

locked together and align the pilots with respect to the other walls of the casting cavities at the various temperatures of the casting operations.

5 The adjacent faces of the mold halves 12 and 13 are suitably recessed to provide gate, riser and casting cavities therebetween, there being in the mold illustrated herein two casting cavities 22, each provided with a main 10 riser cavity 23 and an auxiliary riser cavity 24. The auxiliary risers 24 are located between the respective casting cavities 22 and the adjacent ends of the mold halves while the main riser cavities are positioned between 15 the casting cavities 22. A compound gate serves to conduct molten metal simultaneously into the adjacent riser cavities 23 and casting cavities 22. Briefly it comprises a common inlet passage, a feeder closely adjacent to and in communication with each 20 of the casting cavities through a short narrow passage and a smoothly curving connecting passage of decreasing cross sectional area extending from the inlet passage to each 25 feeder, these connecting passages each being shaped to form a liquid seal when molten metal is introduced into the inlet passage and to conduct molten metal into the feeder cavity smoothly, and at a rate of speed such 30 that the stream of metal is not broken or agitated sufficiently to result in the formation of a porous casting. The gate as illustrated herein comprises an upright inlet 25 and two sinuous control passages 26 which 35 lead from the bottom of the inlet passage 25 upwardly and outwardly away from each other, then curve and extend downwardly and toward each other, and finally curve downwardly and away from each other in a 40 wide sweeping curve, spreading out into a vertically elongated narrow fan shaped passage 27 which communicates with the adjacent riser cavity 23 through a narrow opening. The walls of each passage 26 converge 45 downwardly to the point where they spread out into the narrow fan shaped passage 27 and cooperate to retard the velocity of the molten metal therethrough so that the metal enters the feeder and casting cavities 50 smoothly and at such a velocity that substantially all agitation or splashing of the molten metal is avoided. Passages 26 extend upwardly above the bottom of inlet 25 and form a liquid metal seal which assists in excluding 55 light impurities from entry into the casting cavity.

The riser cavities 23 and 24 communicate with the casting cavities 22 through vertically elongated narrow openings 23^a and 24^a of the general size and proportions illustrated, disclosed and claimed in U. S. Letters Patent No. 1,296,594 issued March 4, 1919, to Allen B. Norton.

60 Main cores designated as entireties by the characters 28 and each consisting of a plu-

rality of parts, in this instance three parts, extend into the casting cavities 22 to form the inner walls of casting cavities for internal combustion engine pistons and are supported in position therein by engagement 70 of outstanding flanges 29 on the outer ends of the cores with the top surface of the mold halves 12 and 13. These cores are positioned in the casting cavities by keys 29^a on the mold halves which engage the keyways 29^b in one of the core sections and the assembled cores are held assembled when the mold halves 12 and 13 are clamped together and about the cores.

Each casting cavity 22 is provided with two core pins 30 which project thereinto to provide cored-out wrist pin bosses on the piston casting. These core pins 30 are oppositely disposed and in substantial alignment with each other, and the pins 30 in each mold half may be reciprocated simultaneously by actuating means consisting of a shaft 31 having a lever 32 secured to it midway between its ends, and provided with suitable bearings 33 which are fastened to the respective mold halves as by cap screws 34, and also provided at each end of the shaft 31 with pinion gears 35. The pinion gears 35 are adapted to engage with blocks 36 secured to each of the core pins 30 as by removable pins 37, the under surface of each block 36 being provided with a rack 36^a corresponding to the pinion 35. When the arm 32 is moved toward or away from the mold halves it will cause the shaft 31 with the pinions 35 to rotate thereby reciprocating blocks 36 and pins 30. In the outer ends of blocks 36 are secured handles 38 for use in removal of the core pins from engagement with the mold halves, should this become desirable, as for example, to cool the core pins. Since the rack on the underside of blocks 36 extends across the entire lower surface thereof, it will be understood that the pins may be readily removed without disturbing 100 any mold parts. Each lever 32, with its shaft 31, is adapted to reciprocate the core pins 30 in one mold half for each of the casting cavities 22. It will be understood that in this manner one operator can withdraw or assemble the four core pins by a single simultaneous move of his two hands.

Each mold half 12 and 13 is of approximately uniform thickness, between the casting cavities as well as at the points where 120 the core pins 30 enter the latter, as will be noted by reference to Figs. 1 and 3. Means are provided in the mold halves however to support the core pins suitably comprising steel bushings 39 each of about the same 125 length as the thickness of a mold half and an integral flange 40 to seat against the outside of the mold half and be secured thereto as by cap screws 41.

The mold halves 12 and 13 are of unique 130

construction and employ certain inventive features which are more fully set forth and claimed in copending applications, Serial No. 22,549, filed April 13, 1925, of Allen B. Norton and Marius Guyot, and Serial No. 22,766, filed April 13, 1925, of Marius Guyot and Allen B. Norton. These present mold halves are fixed to the mold base at one end and hence tend to expand in a longitudinal direction during the casting operation which expansion can take place only from the pin 9 toward the opposite end of the mold halves. It will be observed that this expansion, although perhaps amounting to only a few thousandths of an inch, would be sufficient to create a misalignment of the mold parts with respect to the mold base, unless the mold base can be made to expand at substantially the same rate and to substantially the same amount as the mold halves or unless other means are provided for maintaining the original alignment of the walls forming the casting cavities. The means herein disclosed for maintaining the original alignment of such mold parts includes the movable pilots 6. As the mold halves 12 and 13 tend to expand lengthwise, the pilots 6 are moved in the mold base 1 by recesses 12^a and 13^a in the mold halves which cooperate with the pilots to position them properly with respect to the casting cavity, thereby maintaining the original alignment of pilots and mold halves under all operating temperatures and conditions of the molds.

In Figs. 5 and 6 is illustrated a modified form of mold base, differing slightly from the base shown in Figs. 1, 2 and 3. This modified base consists of a bottom member 45 similar to member 2 and two top members 46 similar to top member 3 is split lengthwise, each secured to the bottom member 45 as by cap screws (not shown). Pilots 48 of any desired size or shape may be retained between the members 45 and 46 for limited movement to correspond with longitudinal expansion of the mold halves.

Having thus described my invention, what I desire to secure by Letters Patent is defined in what is claimed, it being understood that various changes in the apparatus above described not amounting to invention are considered as falling within the scope of this invention as defined by what is claimed.

55 What is claimed is:

1. A mold having a plurality of casting cavities comprising a mold base, two hinged mold halves fixed at one end thereof and adapted to be moved on the mold base, and pilots movable in and extending above the top of the mold base, the top surface of each of the said pilots cooperating with adjacent surfaces of the said mold halves to form a casting cavity.

2. In a mold having a plurality of casting

cavities the combination of a mold base, hinged mold halves fixed on the base and pilots movably carried by the base and cooperating with the mold halves to form the casting cavities.

3. A permanent mold comprising a mold base, two hinged mold halves movably mounted on the mold base and having their meeting faces recessed to provide the side walls of a plurality of casting cavities, and a plurality of pilots in the mold base each forming the bottom wall of a casting cavity and each being adapted to maintain its original alignment with the mold halves regardless of the differences in temperature in the mold halves and base.

4. A mold for making a plurality of castings simultaneously which comprises a mold base, mold members on the base and expandable lengthwise thereof, the meeting faces of the mold members being recessed to form the side walls of a plurality of casting cavities, and pilots forming the bottom walls of the casting cavities and movable in the base by the said mold members as the latter expand lengthwise.

5. A permanent mold for simultaneously making a plurality of castings comprising a multipart mold base consisting of members spaced apart vertically and pilots movably retained between the said members, mold halves hingedly fixed to the mold base, and cooperating with the pilots and each other to form a plurality of casting cavities, the pilots being movable by the mold halves as the latter expand and contract under varying temperatures thereby maintaining the casting cavity walls in substantial alignment during the casting operation.

6. A multipart permanent mold for simultaneously making a plurality of castings composed of a high melting point metal which comprises a mold base disposed out of direct contact with the molten metal, mold halves contacting directly with the molten metal and fixed at one end to the base and pilots in the mold base contacting directly with the molten metal and movable in the base by the mold halves and coincident with longitudinal expansion of the mold halves.

7. A permanent mold comprising a mold base consisting of members spaced vertically and a pilot movably retained between the members and projecting through and above one of the members, a hinge pin extending above the base at one end thereof, mold halves rotatably secured to the hinge pin to swing on the mold base, the mold halves being cut away to engage the sides of the pilot which project above the base and recessed thereabove to form the side walls of a casting cavity, the bottom walls of the cavity being formed by the said pilot.

8. A mold having a plurality of casting cavities comprising a mold base, two sub-

- stantially non-warping hinged mold halves fixed at one end thereof and adapted to be moved on the mold base, and pilots movable in and extending above the top of the mold 5. base, the top surface of each of the said pilots cooperating with adjacent surfaces of the said mold halves to form a casting cavity.
9. A multipart permanent mold for simultaneously making a plurality of castings 10 composed of a high melting point metal which comprises a mold base disposed out of

direct contact with the molten metal, substantially non-warping mold halves contacting directly with the molten metal and fixed at one end to the base and pilots in the mold base contacting directly with the molten metal and movable in the base by the mold halves and coincident with longitudinal expansion of the mold halves.

In testimony whereof I hereunto affix my signature this first day of April, 1925.

MARIUS GUYOT.
